Primary Examiner — Selina Sikder(74) *Attorney, Agent, or Firm* — Olive Law Group, PLLC(57) **CLAIM**

The ornamental design for a remote control key, as shown and described.

DESCRIPTION

FIG. 1 is a top, front and right side perspective view of a remote control key, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The evenly broken lines show the features of the remote control key that form no part of the claimed design. The unevenly broken lines illustrate the boundary of the enlarged view that form no part of the claimed design.

1 Claim, 9 Drawing Sheets(56)
